(57) CLAIM

The ornamental design for a dirty clothes basket, as shown and described.

DESCRIPTION

FIG. 1 is a front, right and top perspective view of a dirty clothes basket, showing my new design.

FIG. 2 is a front, left and top perspective view thereof.

FIG. 3 is a rear, left and bottom perspective view thereof.

FIG. 4 is a front view thereof.

FIG. 5 is a rear view thereof.

FIG. 6 is a left side view thereof.

FIG. 7 is a right side view thereof.

FIG. 8 is a top view thereof.

FIG. 9 is a bottom view thereof; and,

FIG. 10 is a top perspective view of the dirty clothes basket, when on the cover is in a closed state.

The broken lines in the figures illustrate portions of the dirty clothes basket that form no part of the claimed design.
